UNITED STATES PATENT OFFICE.

ELIHU THOMSON, OF LYNN, MASSACHUSETTS.

DYNAMO-ELECTRIC MACHINE.

SPECIFICATION forming part of Letters Patent No. 333,573, dated January 5, 1886.

Application filed August 10, 1885. Serial No. 173,960. (No model.)

To all whom it may concern:

Be it known that I, ELIHU THOMSON, a citizen of the United States, and a resident of Lynn, in the county of Essex and State of Massachusetts, have invented certain new and useful Improvements in Dynamo-Electric Machines, of which the following is a specification.

The present invention relates to improvements in dynamo-electric machines and also in electric motors, since some of the constructions herein described are applicable to both.

The object of the invention is to secure a simple and efficient dynamo-electric machine adapted to furnish a constant potential, or nearly so, and an electric motor for the purpose of maintaining, when fed by a current of constant potential, a nearly constant speed.

Figure 1 represents in elevation and partly in section a machine constructed in accordance with my invention. Fig. 2 is an end elevation of the same. Fig. 3 is a diagram of the circuits. Fig. 4 is an exterior view of the armature-core unwound. Fig. 5 is a longitudinal section of the armature-core. Fig. 6 illustrates the winding of the armature. Fig. 7 is a diagram of the winding. Fig. 8 is a side view of the commutator-cylinder. Figs. 9, 10, 11, and 12 are diagrams illustrating the magnetic actions during operation, and Fig. 13 an adjustable arrangement sometimes employed.

In Fig. 1, F is a section of the core of one of the field-magnets, which is flanged, so as to be joined to a corresponding flange of the field-magnet F' at the other end by an exterior casting of iron or iron bars, 11. Each of these field-magnets consists, as shown, of a short cylinder, of iron, or other suitably-shaped piece, the end of which presented to the armature A is hollowed out to form a concavity conforming to the spherical outline of the armature. Exteriorly to the part F, and surrounding it, as usual, are coils of copper wire, C C, constituting the coils of the field-magnet proper. The armature A, constructed as hereinabove described, is mounted on a shaft seen end on at X in Fig. 1, and seen as extending from the pulley end across the machine in Fig. 2. A suitable frame with feet G G is provided for the support of the shaft and various parts of the machine. The armature-

core is wound with wire, which revolves along with the said core. The mode of winding will be described hereinafter. Supported so as to surround the armature-core A, but not moving with it, is a coil or coils, B B' B', placed, as shown in Fig. 1, so as to permit the free revolution of the armature internally thereto. These coils may be described as stationary hoops, of wire, preferably bent to avoid the shaft, and whose planes of position are inclined, preferably as from B to B and B' to B', in such manner that the inclination is backward with reference to the direction of revolution, as indicated by the arrow. The purpose of this arrangement will be afterward described.

In Fig. 2, P is the driving-pulley. The bearings of the shaft are shown at D and E, which bearings are suitably supported on iron frame-work carrying the feet G G, and extending from the flanges on F F', being securely bolted thereto, as in prior constructions shown by me. The bearing E is on an arm or bracket, H, fastened to the frame-work connecting to the flange t of the field-magnets, which bracket serves also as a support for the yokes and attachments of the commutator-brushes. The commutator is indicated at K. The further details of these parts will be described later.

In Fig. 3 the mode of connecting is shown. The commutator-brushes J J, indicated as bearing on the commutator-cylinder K in a suitable position, are attached, respectively, to connections leading through the coils C C, as shown, while the circuit from J J is continued through the coils B B and B' B', themselves arranged in series or in multiple arc with each other, and traversed by the current generated by the machine and supplied to the electric mains. The work, such as a number of incandescent lamps, W W, arranged in multiple arc from the mains or conductors leading from the machine, (the number of which lights W W may be varied *ad libitum*,) is fed by the current developed, save that portion which passes through C C. The coils C C are therefore in shunt to the work W W.

In Fig. 4 the armature-core A is shown mounted on a shaft ready to be wound. It consists of a portion of a sphere, or a sphere from which two segments have been taken in

the polar portion, through which the shaft passes so as to leave two flattened surfaces thereat. The core is built up bodily, either of a mass of iron wire wound around a shaft 5 between suitable guiding plates, M N, Fig. 5, or, preferably, of a number of sheets of iron or iron disks of varying diameter, as seen in Fig. 5, piled up around a suitable form carried by the shaft and secured between such plates.

10 Projecting pins at *p p* serve as guides in winding the armature, and are usually carried by the plate or flange at each end of the armature-core.

I find it of considerable advantage in the 15 use of such an armature-core to construct it with connecting-wires L L, equal in number to the segments to be used in the commutator, or to the number of coils or divisions of a single coil on the armature. These leading-

20 wires or connecting-wires L L pass, as shown in Fig. 5, (sectional view,) from near the periphery of the armature inwardly through a proper space provided in the armature-core itself and out through the end plate, N, along 25 the shaft. These leading-wires are carefully insulated, and preferably inclosed between disks of insulating material, (shown in black,) allowing them to be spread out radially from near the shaft.

30 Other constructions permitting the carrying of the wires L L from along the shaft to a point at or near the greatest exterior circle of the armature-core will suffice, but the construction shown is simple and efficient. The plates

35 M N may be keyed securely to the shaft, and where it is not desirable to have the sheet-iron disks extend close to the shaft an interior tube or other support may be provided to hold them concentrically with said shaft. It is also

40 preferable to leave small spaces *g g* between the disks at suitable points, blocks of any suitable material being inserted to hold them apart. These spaces permit connection-currents to circulate through the body of the 45 armature and help to dissipate heat, though it is desirable to construct the armature of sheets of iron of such thinness that very little heat is generated during the changes of its magnetism.

50 The mode of winding may be described as follows, and the result of the winding is exhibited at Fig. 6: Beginning at any convenient point, a suitable wire or several wires are carried around the armature in diametrical- 55 ly-opposite spaces between the pins *p p*, provided as guides in winding, the space for wire being filled only half. When this is done, the wire is carried diagonally into the next space, and this passage is made on the

60 armature, as seen in Fig. 6, near that portion of the core having the largest diameter and where a space is left vacant between the coils, due to the form of the armature and its varying diameter as the coils of wire pass over it.

65 This will be understood when it is stated that the periphery at which the pins *p p* are located is smaller than that at the middle line, (dot-

ted in the figure,) so that wire which follows and fills the spaces between the pins leaves open spaces between the coils at the central 70 position; but the wires L L, through which connection is made to the commutator-cylinder, are arranged to have one end of each open into one of these spaces and in regular succession, so that a joint from said wire is easily 75 made with the projecting end of L and the portion of the coil passing near thereto from one coil-space to another. Thus the wire *a* in Fig. 6 will be connected to L², one of the terminal wires projecting radially from the armature-core, and being a continuation of a corresponding wire led along the shaft, as seen in Fig. 5.

In armatures wound as ordinarily upon cylindrical cores no such facility for the connection of coils exists, and my construction therefore furnishes a simple method, differing from others, of winding a continuous wire around the armature-core, securing ample space for the production of a good joint with 85 the commutator leading-wires, and securing simplicity and ease of winding. To complete the winding of the armature, it is only necessary to continue, half-filling the coil-spaces with wire in regular succession around the core, 90 and making the suitable joints with the leading-wires until the core is covered with wire. At this time it will be found that one-half the leading-wires have been connected to the wire 95 of the winding. It is now only necessary to 100 continue the winding, filling the spaces completely, while the joints are made with the connecting-wires between what now become the exterior coils of the system. The finishing of the winding takes place in connecting 105 the first end to the last end of the wire used in the winding.

To elucidate the winding, Fig. 7 may be referred to, where there are supposed to be eight leading-wires, L L L L, &c., and eight coils 110 consisting of two series, the under series and the outer series, all constituting a single unbroken wire. Assuming the coil 1 to have been laid on, then in passing to the adjoining space and coil 2 described the connection to 115 a leading-wire is made, and this is repeated in passing from coil 2 to 3 and from 3 to 4, at which moment the armature-core has received the entire first series of coils on its exterior. Then a similar joint is made in passing 120 to the first coil of the second series, and so between the coils of the second series and the last joint to the leading-wire in passing from the last coil of the second series to the first coil of the first series. Any number of coils 125 may be thus wound on the armature if the number of spaces provided therefor is sufficient. The winding, it will be seen, is similar to what is known as the "Siemens winding," but the connections are taken out in an entirely 130 novel manner, permitting the close winding of a single wire or group of wires. The wires L running along the shaft from the coils of the armature to the commutator-segments K, re-

spectively, are insulated from each other, as usual, and are shown in Fig. 8. The revolution of the armature in the magnetic field generates currents in its coils which, as in the Siemens 5 construction, are carried out to the strips in the commutator, and are there conveyed to the circuit by the brushes bearing upon the commutator. The position at which the brushes are set on the neutral line with an enormous 10 strength of field-magnetism, and an armature-core whose magnetic effects are comparatively very weak, as when but little current flows in its coils, or when a few convolutions exist upon it, will be in a line almost at right angles with 15 the magnetic line induced by the field-poles, as is well understood. It is inconvenient, however, to give to the machine such enormous field strength and to diminish the armature convolutions to the degree required, as it limits 20 the capacity of the machine, and makes the field expensive to produce. In consequence a lower field strength is selected and an armature of more convolutions utilized; but in this case the position of the neutral line at which 25 the brushes should be placed is forward to a greater or less degree, depending upon the work demanded of the armature. Thus, in Fig. 9, N S represent the field-poles; A, the revolving armature; K, the commutator, and 30 B² the brushes. When the current is doing little work—that is, when the current flowing through the coils is small, as for a few lamps or devices supplied in multiple arc—the brushes B² B² should be placed to touch the commutator 35 on a line, as t t, nearly at right angles to a line joining the centers of the field-poles. In practice a slight inclination is found in the direction of revolution, depending on the speed of rotation of the armature and other causes. 40 If, now, the load on the armature or the work done by it be increased, the strength of the field-magnetism remaining the same, or even being increased to a limited extent, the position at which the brushes should touch the 45 commutator to avoid spark will move forward, as at t' t', Fig. 16, owing to the reaction between the magnetism of the armature and the magnetism of the field, and the consequent distortion of the magnetic field. It is desirable, 50 however, to avoid the necessity of constant readjustments according to the load. To secure this end, I place around the armature-core, as in Figs. 1 and 3, the coarse-wire coils B B B' B', and in an angular position backward. If the coils 55 be made movable, this position may readily be adjusted. These coils are represented in Fig. 10, and, as has been stated, Fig. 3, are traversed by the current fed to the work, which current is of varying amount. The action of 60 the currents traversing the coils B B B' B' upon the armature-core is such as to develop magnetism in it in a direction at right angles to their plane, or axially to them, with the result of readjusting the neutral line as the current 65 increases in the armature to a practically constant position a little forward of a line join-

ing the field-poles N S centrally. This neutral line so established is shown in Fig. 10, t' t'.

To make clear the manner in which the results are secured, I refer to Fig. 11 as exemplifying the magnetic actions when the coils B B B' B' are absent. The field-poles tend to establish in the armature-core a polar line or magnetic condition whose direction is seen in the line N' S', while the current generated in the armature itself tends to establish a polar line in the same armature-core in the line N² S². The resultant line of real magnetism existing in the armature-core will, however, be N³ S³, a line drawn intermediately between the line N' S', due to the inductive influence of the field, and N² S², due to the currents flowing in the armature, but approaching more nearly the direction of N' S', on account of the superiority of the magnetic effects of the field to that of the armature-currents. The direction of revolution in all these cases is indicated by a curved arrow.

In Fig. 12, N' S' represent, as before, the induced magnetism or axial line in the armature-core induced by the field, while the line N⁴ S⁴, at right angles to coils B B and B' B', represents the line of magnetism induced by the action of the coils B B B' B', the direction of the current sent through such coils being made such as will assist the action of the field-magnets themselves upon the armature-core, but will produce a magnetic axis not quite coinciding with that produced by the field-magnets themselves, but which will be displaced, as indicated at N⁴ S⁴, instead of being in the direction N' S', which would have been the direction had the coils B B B' B', instead of being inclined, been placed with their planes at right angles to the line N S, or with their planes parallel with the plane of the field-magnet wire C C, Fig. 3, with the current unchanged in direction.

In Fig. 12 the line N² S² represents, as before, the direction of the magnetic axis induced by the flow of current in the armature-coils. It will now be easily seen that should the influence of the coils B B B' B' exist alone with that of the armature-currents, supposing such were possible, a resultant magnetic axis would be produced, which might easily be made coincident with the line N' S', or the direction in which magnetism is induced by the field-magnets themselves acting alone; hence by the construction which I have described it is easy to secure a neutral point a little forward of the line at right angles to that joining the axis of the field-poles, and which line undergoes practically no change from light load to full load, or from weak current developed by the armature to the strongest currents which it may yield, this feature being due to the stationary armature-encircling coils B B B' B' overcoming the distortion of the magnetic field by their being placed in an inclined position, as described.

I find, also, in the practice of my invention

that the proportions of the coils B B B' B' to the rest of the circuit may be made such as to secure a constant potential at the commutator-brushes, and a difference of electro-motive force at the terminals of the machine of constant amount, this second feature being alike due to the effect of the said coils acting upon the armature-core inclosed by them so as to prevent a weakening of the magnetic actions 10 when the armature-coils are discharging heavy currents.

The position of the coils B B B' B' can be made adjustable by mounting them upon a suitable support permitting their movement. 15 This is indicated in Fig. 13 as consisting of a stationary ring, R², and a second ring or portions of a ring bearing on the interior surface, to which second portions the coils B B B' B' are secured. A proper handle, H', attached 20 to the parts upon which the said coils are mounted, may be provided to set the coils in position. When the proper position has been selected, the screw D' serves merely to clamp the portions holding the coils B B to the outer 25 ring R². This position having been selected, requires no change, unless the other portions 30 of the apparatus are changed. It is preferable, however, to select a fixed position for the coils and use them at all times in the best 35 fixed position, constructing the machine so as to dispense with the adjustability of the coils B B B' B', thereby securing cheapness and greater simplicity. I do not, however, wish to limit myself to the use of coils in a fixed 40 position merely.

I have described my present invention as applicable to a dynamo-electric machine. The improvements are equally applicable to the case of motors, which are simply reversed dynamo-electric machines, and the changes which 45 are to be made in applying my invention to convert the dynamo-electric machine into a motor are only those changes which are made usually in such cases, and well understood by those skilled in the art. I have therefore not 50 deemed it necessary to describe those alterations, which are simply those of connection to the feeding-circuit.

The mechanical elements embodied in my 55 present invention will be unchanged, as the alteration of circuits will involve no change of structure.

What I claim as my invention is—

1. In a dynamo-electric machine or motor, field-magnet cores wound with wire connected in derived circuit or shunt to the work, and an armature surrounded by stationary coils traversed by the main current of the machine.
2. In a dynamo-electric machine or motor, an armature surrounded by stationary coils applied in the manner described to correct the tendency to distortion of the magnetic field by the reaction of armature and field-magnetism.
3. In a dynamo-electric machine or motor, the combination, with the revolving armature, of stationary coils mounted on an adjustable

support, whereby their plane of winding may be varied with relation to the line of field-magnetism, as and for the purpose described.

4. In a dynamo-electric machine, an armature-core surrounded by coils of wire placed in an inclined position with respect to the magnetic axis of the field-magnets. 70

5. In a dynamo-electric machine, stationary coils surrounding only the armature-core of 75 the machine and set in an inclined position, as described.

6. In a dynamo-electric machine or motor, an armature wound with a continuous wire and having connections therefrom to the commutator, in combination with commutator-brushes connected to a system of field-magnet coils in derived circuit around the work, and connected in series to the work through a system of stationary coils surrounding the armature-core. 85

7. In a dynamo-electric machine, an armature-core constructed with spaces leading to the interior of said core, in combination with leading-wires passing through such spaces 90 from the armature-coil system to the segments of the commutator.

8. In a dynamo-electric machine, leading-wires from the commutator passing into the body of the armature-core and outwardly toward the greatest periphery of said core, as 95 described.

9. In a dynamo-electric machine or motor, leading-wires connected to the armature-coils and passing inwardly through the armature- 100 core itself, as and for the purpose described.

10. In a dynamo-electric machine or motor, an armature circular in section transverse to its axis, and having commutator leading-wires passing through openings in the armature- 105 core, as and for the purpose described.

11. An armature-core composed of end plates, M N, a series of disks of varying diameter, spaces g g, dividing the disks into groups, and leading-wires inserted into passages made 110 in the body of the armature-core, as described.

12. In a dynamo-electric machine, a system of coils wound upon an armature whose peripheral surface is a portion of a sphere or ellipsoid, said system of coils being wound in 115 two series overlying and underlying, with the wire of one coil in a series passing to the next coil in the series diagonally across the space existing between the coils at or near the place of greatest peripheral diameter of the armature. 120

13. In a dynamo-electric machine or motor, a spherical armature wound with a series of coils connected to one another diagonally across the spaces at or near the greatest peripheral diameter of the armature-core. 125

14. In a dynamo-electric machine or motor, leading-wires passing through a portion of the armature core and connected with the coil system at the places where the coils are separated 130 by passing over the greatest peripheral diameter of the curved armature-core, as described.

15. In a dynamo-electric machine or motor, an armature wound with a continuous conductor placed in an underlying and overlying series of coils or coil-sections joined to the 5 leading-wires from the commutator at points where the armature conductor or coil passes diagonally from one section or coil to the succeeding section or coil, as described.

16. In a dynamo-electric machine having its 10 field-magnet coils connected in derived circuit to the work, a set of coils inclined to the magnetic axis of the field-magnet and connected in series with the work.

17. In a dynamo-electric machine or motor, the combination of field-magnet coils, and coils 15 set at an angle to the magnetic axis of the field, one set of coils being in series with the work and the other in derived circuit thereto.

Signed at Lynn, in the county of Essex and State of Massachusetts, this 6th day of August, 20 A. D. 1885.

ELIHU THOMSON.
